UNITED STATES PATENT OFFICE.

GEORGE A. CROSSMAN, OF SWAMPSOFT, MASSACHUSETTS.

DESIGN FOR A SCRAPING-TOOL.

SPECIFICATION forming part of Design No. 27,141, dated June 1, 1897.

Application filed September 16, 1896. Serial No. 606,058. Term of patent 14 years.

To all whom it may concern:

Be it known that I, GEORGE A. CROSSMAN, of Swampscott, in the county of Essex and State of Massachusetts, have invented a certain new and original Design for Scraping-Tools, of which the following is a specification.

This invention relates to a new and original design for a scraping-tool; and it consists in the novel features of shape and configuration 10 hereinafter fully described and claimed, and clearly illustrated in the drawings.

Figure 1 is a plan view of a tool for scraping or removing mud and dirt from vehicle-wheels embodying my design. Fig. 2 is a 15 perspective view of the same.

a represents the tool, which has a reentrant or concave curve *b*, which is an arc of a circle,

being a substantial semicircle. The handle of the tool is shown as being rounded at the end, as at *c*, with straight sides *d*, connected with the ends of the curved edge *b* by convex-curved edges *e*.

I claim—

The design for a scraping-tool, substantially as shown and described.

In testimony whereof I have signed my name to this specification, in the presence of two subscribing witnesses, this 10th day of September, A. D. 1896.

GEORGE A. CROSSMAN.

Witnesses:

C. F. BROWN,
A. D. HARRISON.
